UNITED STATES PATENT OFFICE

SEDWICK N. WIGHT, OF ROCHESTER, NEW YORK, ASSIGNOR TO GENERAL RAILWAY SIGNAL COMPANY, OF ROCHESTER, NEW YORK

INTERLOCKING SYSTEM FOR RAILROADS

Application filed November 8, 1929. Serial No. 405,625.

This invention relates to interlocking systems, and more particularly to the provision of means for controlling an interlocking plant located at a great distance from the dispatcher's office economically and over a comparatively few line wires.

When two railroad tracks cross each other at the same grade it is necessary to provide interlocking means to prevent a collision between two trains at such crossing. In accordance with the usual practice there are not only provided signals of the stop-and-stay type at the approach to such a crossing, but derails are also provided, and these derails are in their active derailing position normally and are only cleared when the derails of the conflicting route are in their active position. In accordance with the present invention it is proposed to operate the derails and signals of one of the conflicting tracks over separate circuits, and to indicate over these same circuits when the derails are operated, when a train passes over such derails and which of the signals is in a proceed position.

Other objects, purposes and characteristic features of the invention are in part apparent from the accompanying drawings and will in part be pointed out in the description hereinafter.

In describing the invention in detail reference will be made to the accompanying drawings, in which the portion in the dotted rectangle at the left indicates the apparatus located in the interlocking tower and the remaining portion indicates the apparatus at the distant railroad crossing.

Referring to the drawings there have been shown an east and west track EW having rails 1, and a north and south track NS having rails 2, of two conflicting railway systems. The present invention has been shown applied to the east and west system, which has associated therewith an east bound derail DRE and west bound derail DRW. These derails are each operated by a switch machine mechanism of the usual construction, which has been conventionally illustrated. Train travel is directed over the derail DRE through the medium of the stop-and-stay signal SE and train travel is directed over the west bound

derail DRW by the stop-and-stay signal SW, home relays EH and WH being provided for controlling these signals, respectively, in accordance with traffic conditions. The track section between the signals SE and SW is insulated from the remaining track by insulating joints 3, and is provided with the usual track circuit including a track relay T and a track battery 4. The derails DRE and DRW are controlled through the medium of a control relay 2Z, whereas the signals SE and SW are controlled in accordance with traffic conditions by the control relay 1Z, the operated condition of the track relay T also entering into the control of the signals SE and SW, whereas the operation of the derails DRE and DRW is dependent upon the relay 2Z and the condition of train travel as determined by an approach locking arrangement such as shown in my prior application, Ser. No. 120,423, filed July 3, 1926, as has been conventionally shown by the approach locking relay AL. There are also provided relays 2OS and 2WP the purpose of which will be described hereinafter.

In the interlocking tower is reproduced in miniature the track layout of the distant interlocking plant. Associated with this miniature track layout is a miniature west bound signal *sw* and a miniature east bound signal *se*, an indicating lamp *te* being provided to indicate occupancy of the track circuit at the distant interlocking plant, and the indicating lamp *I* indicating operation of the derails DRE and DRW. There are also provided in the interlocking tower IT relays IR, 2R, and IX, the purpose of which will be pointed out in the operation of the system hereinafter. Having now pointed out the various elements of the system, it is deemed expedient to take up the operation thereof to observe their coaction.

Operations.—Let us assume that the interlocking operator has been informed by suitable means, not shown, that there is an east bound train approaching on the track EW, and that he wishes to clear the signal SE to allow such train to pass over the railroad crossing. In order to do this he will first be required to operate the two derails DRE

and DRW to their abnormal ineffective position. This will be done by moving the lever L^2 to the right thereby closing the following circuit for the relay 2Z: beginning at the positive terminal of the battery 10, wires 11 and 12, lever L^2 , wires 13 and 14, winding of the relay 2R, line wire 15, front contact 16 of the relay 2OS, wire 17, winding of the relay 2Z, wires 18 and 19, contact 20 of the signal SS, wire 21, signal blade contact 22 of the signal SN, wires 23 and 24, common return wire C, wires 25 and 26, back to the midpoint of battery 10. It will be noted that this circuit cannot be completed unless the signals SS and SN of the conflicting track are in their stop position. Completion of this circuit effects energization of the control relay 2Z and the indicating relay 2R.

With the control relay 2Z energized to the right, it being assumed that current flowing from the positive terminal of the battery 10 will operate relay 2Z toward the right, the following circuits for energizing the derail machines DRE and DRW are closed, this on the assumption that the approach locking relay AL is energized and that the approaching train has not yet approached within the approach locking zone preferably extending braking distance in the rear of the signal SE:—beginning at the terminal B of a suitable battery, front contact 28 of the approach locking relay AL, wire 29, contact 30, wire 31, polar contact 32, of the control relay 2Z assuming its right-hand position, wire 33, and then the two circuits divide through wires 34 and 35 to the two derail machines DRE and DRW, and thence to the common return wire C connected to the other terminal of said battery. The completion of these circuits causes operation of the derail machines DRE and DRW, and as soon as these machines have been unlocked the following circuit for the relay 2WP is broken: beginning at the terminal B, wire 36, contact 37 of the derail machine DRE, wires 38, 39 and 40, contact 41 of the derail machine DRW, wires 42 and 43, winding of the relay 2WP, to the terminal C connected to the other side of said battery. The breaking of this circuit for the relay 2WP causes the contact 45 of this relay 2WP to assume its retracted position, thereby reversing the polarity of the current applied to the relay 2OS, and causing the relay 2OS to assume its de-energized position and a moment thereafter again assume its energized position. This is accomplished by opening of a circuit starting at the negative terminal of battery 50 through 46, 47, 48, 49, 44, 45, 8, 2OS, 9 and 56; and closing of a circuit starting at the positive terminal of battery 50 through 7, 45, 8, 2OS, 9 and 56. By reason of inclusion of the signal blade contacts 47 and 49 in the first one of these circuits, operation of the derails cannot be initiated unless the signals SE and SW are at stop, it being

understood that relay 2Z cannot be operated unless relay 2OS is energized, but if relay 2Z has once been energized it may be held up through back contact 16 of relay 2OS, the relay 2Z being sufficiently slow dropping as conventionally shown to prevent it dropping during dropping of the contact 16.

De-energization of the relay 2OS opens the line circuit including the line wire 15 and effects de-energization of the relay 2R in the interlocking tower IT, but such de-energization of relay 2OS does not effect de-energization of the control relay 2Z, because this control relay 2Z is maintained stuck up through the following stick circuit: beginning at the positive terminal of the battery 50, wire 51, contact 52, wire 53, neutral contact 54 of the relay 2Z, wire 55, contact 16 of the relay 2OS in its retracted position, wire 17, winding of the relay 2Z, wires 18 and 19, contact 20 of the signal SS, wire 21, signal blade contact 22 of the signal SN, wires 23 and 56, back to the midpoint of the battery 50. Momentary de-energization of the relay 2R causes the following circuit to be momentarily completed for the indicating lamp I: beginning at the positive terminal of the battery 10, wires 11 and 12, contact of lever L^2 , wires 13 and 57, back contact 58 of the relay 2R, wire 59, contact 60 of relay 1R, wire 61, indicating lamp I, wires 62, 63, 64, and 65 back to the midpoint of the battery 10. This momentary illumination of the indicating lamp I informs the operator that the derails have been started on their cycle of operation from their active to their inactive position or vice versa, and when these derails have completed this cycle of operation the same energizing circuit except that contacts 37 and 84 assume their dotted position for the relay 2WP is again completed, the contact 45 of this relay is operated to its attracted position, thereby again reversing the polarity of current applied to the relay 2OS and again effecting momentary illumination of the indicating lamp I, for reasons just explained.

When the operator has received this second flash of the indicating lamp I he will return his lever L^2 to the neutral position and will operate the lever L^1 to the right-hand position in order to clear the east bound signal SE. This movement of the lever L^1 effects closure of the following circuit:—beginning at the positive terminal of the battery 10, wires 11 and 66, contact of the lever L^1 , wire 67, winding of the relay 1R, line wire 68, front contact 69 of the track relay T, wire 70, winding of the relay 1Z, wires 71 and 19, contact 20 of the signal SS, wire 21, contact 22 of the signal SN, wires 23, 24, C, 25 and 26, back to the midpoint of battery 10. It will be noted that the circuit just traced cannot be closed unless the track circuit containing the track relay T is unoccupied. The completion of the circuit just traced energizes

the control relay 1Z toward the right, the relay 1Z being connected to so operate, and with this relay 1Z energized toward the right the east bound signal SE is permitted to clear, providing traffic conditions in advance 5 of the signal SE, are proper as manifested by the home relay EH and providing that both the derail DRE and the derail DRW have been moved to their abnormal closed track position.

This circuit for the signal SE may be traced as follows:—beginning at the terminal B of a suitable battery, neutral contact 72 of the relay 1Z, wire 73, polar contact 74 of the relay 1Z toward the right, wire 75, neutral contact 76 of the home relay EH, wire 77, polar contact 78 of the home relay EH toward the right (assuming clear traffic conditions ahead) clear wire 79, mechanism 20 of the signal SE, (for its colored signal lamp if a light signal is used) wires 80 and 81, contact 82 of the derail DRE, wire 83, contact 84 of the derail DRW, wire 85 to the other terminal C of said battery. It is thus 25 noted that the signal SE cannot clear unless the operator has operated the control relay 1Z toward the right, traffic conditions as manifested by the home relay EH are clear, and unless the derail machines DRE and 30 DRW are in their closed track position. The completion of the circuit for energizing the control relay 1Z also effects energization of the indicating relay 1R. Also, with the lever L¹ in its right hand position the relay 1X 35 is energized to the right, for obvious reasons. With the relay 1R energized and the relay 1X energized toward the right, the following circuit for the miniature signal se is closed: beginning at the positive terminal of the battery 10, wires 11 and 66, contact of the lever L¹, wires 87 and 88, front contact 89 of the relay 1R, wire 90, contact 91 of the relay 1X toward the right, wire 92, lamp of the miniature signal se, wires 93 and 65, back to the 45 midpoint of battery 10.

If now the train in question accepts the signal SE and proceeds into the track section between the signal SE and SW, the track relay T is de-energized, thereby opening its contact 69 and effecting de-energization of the control relay 1Z and the indicating relay 1R. With the relay 1R assuming its retracted position and the lever L¹ in its right-hand position the following circuit for the track 50 occupancy indicating lamp te is closed: beginning at the positive terminal of the battery 10, wires 11 and 66, contact of the lever L¹, wires 87 and 88, contact 89 of the relay 1R in its retracted position, wire 95, signal lamp te, wires 96, 64 and 65, back to the midpoint of battery 10. Also, de-energization of the indicating relay 1R will effect extinguishment of the signal lamp se, so that the operator 55 is informed that the train is passing

through the track section between the signals SE and SW.

By reason of the fact that the approach locking relay AL is controlled by an approach locking circuit such as disclosed in 70 my prior application, to which reference has been made, the derails DRE and DRW cannot be operated if there is a train approaching from either direction, unless this train has accepted the distant signal (not shown) 75 at caution or stop, all as explained in said prior application. From this it will appear that the derail machines DRE and DRW cannot be operated in the face of an approaching train. Further, it will be noted that the 80 signals SE and SW cannot be cleared unless both derails are in their abnormal continuous track position.

Applicant has thus provided a system requiring only two line wires and a common 85 return wire for safely operating the derails and signals at a railroad crossing, the circuit arrangement being such that the operator is informed as to the operation of the derails, the position of signals and the 90 occupancy of the track section in which such derails are located, this system having all of its interlocking features located at the distant interlocking plant, so that any line trouble between the distant interlocking plant 95 and the interlocking tower cannot possibly cause false operation of the derails or the clearing of signals, unless it is safe to so operate them. In practice the track NS of the other system will be protected by suitable 100 interlocked signals which are preferably controlled in the same way.

Having thus shown and described one rather specific embodiment of the present invention it is desired to be understood that the 105 particular circuit arrangement illustrated has been selected to facilitate description of the invention, and its operating characteristics and underlying principles of operation, and has not been selected with the intent of 110 showing the scope of the invention or the exact construction preferably employed in practicing the same, and that various changes, modifications, and additions may be made to adapt the invention to the particular railway 115 system to which it is to be applied, all without departing from the spirit or scope of the invention of the idea of means underlying the same, except as demanded by the scope of the following claims.

What I claim as new is:—

1. In a remotely controlled interlocking system, the combination with two railroads crossing each other, of derails on one of said roads to prevent a train on said road crossing 125 the other road, a control relay for said derails for controlling said derails effective only if signals governing traffic over the other road are at stop, a distant interlocking tower, a circuit including said control relay leading 130

to said tower, a track circuit for manifesting the passage of a train over said derails including a track relay, a front contact of said track relay included in the circuit for said control relay, indicating means at said tower included in the circuit of said control relay, and a lever for controlling the flow of current in said control relay, whereby said derails can be operated and the occupancy of said track circuit can be indicated over the same line circuit.

2. In a remotely controlled interlocking system, the combination with two railroads crossing each other, of derails on one of said roads to prevent a train on said road crossing the other road, a control relay for controlling said derails effective only if signals governing traffic over the other road are at stop, a distant interlocking tower, a circuit including said control relay leading to said tower, a track circuit for manifesting the passage of a train over said derails including a track relay, a front contact of said track relay included in the circuit for said control relay, indicating means at said tower included in the circuit of said control relay, a lever for controlling the flow of current in said control relay, whereby said derails can be operated and the occupancy of said track circuit can be indicated over the same line circuit, signals associated with said derails, and other means for controlling said signals from said distant tower.

3. In a remotely controlled interlocking system, the combination with two railroad systems crossing each other, of wayside signals on one system for blocking the movement of trains over said crossing, derails associated with said signals for enforcing obedience of trains to said signals, a derail relay controlled from a distant tower for controlling said derails, approach locking means for preventing operation of said derails by said derail relay unless there is no train approaching in an approach zone which did not pass an adverse signal, a signal control relay controlled from said distant tower for controlling said signals, and means for preventing control of said signals by said signal relay unless traffic conditions in advance of such signals are favorable.

4. In a remotely controlled interlocking system, the combination with two railroad systems crossing each other, of wayside signals on one system for blocking the movement of trains over said crossing, derails associated with said signals for enforcing obedience of trains to said signals, a derail relay controlled from a distant tower for controlling said derails by said derail relay unless there is no train approaching in an approach zone which did not pass an adverse signal, a signal control relay controlled from said distant tower for controlling said signals, means for preventing control of said signals

by said signal relay unless traffic conditions in advance of such signals are favorable, other signals on said other railroad system for governing the movement of trains over said crossing, and means for preventing operation of said derails unless said other signals are at stop.

5. In a remotely controlled interlocking system, the combination with two railroad systems crossing each other, of wayside signals on one system for blocking the movement of trains over said crossing, derails associated with said signals for enforcing obedience of trains to said signals, a derail relay controlled from a distant tower for controlling said derails, approach locking means for preventing operation of said derails by said derail relay unless there is no train approaching in an approach zone which did not pass an adverse signal, a signal control relay controlled from said distant tower for controlling said signals, means for preventing control of said signals by said signal relay unless traffic conditions in advance of such signals are favorable and means for indicating at said tower the passage of a train over said derails.

6. In a remotely controlled interlocking system, the combination with two railroad systems crossing each other, of wayside signals on one system for blocking the movement of trains over said crossing, derails associated with said signals for enforcing obedience of trains to said signals, a derail relay controlled from a distant tower for controlling said derails by said derail relay unless there is no train approaching in an approach zone which did not pass an adverse signal, a signal control relay controlled from said distant tower for controlling said signals, means for preventing control of said signals by said signal relay unless traffic conditions in advance of such signals are favorable, other signals on said other railroad system for governing the movement of trains over said crossing, means for preventing operation of said derails unless said other signals are at stop, and means for indicating at said tower the passage of a train over said derails.

7. In a remotely controlled interlocking system, the combination with two railroads crossing each other, of derails on one of said roads for preventing a train on said road crossing the other road, signals for governing the movement of trains over said derails, power operated means for operating said derails, a control relay for controlling said power operated means and controlled from a central office, means for indicating at said office the response of said power operated means to said control relay, other signals on the other of said roads for governing the crossing of trains over said one road, means for preventing operation of said power operated means if one of said other signals indicate

cates proceed, and means for clearing said first mentioned signals effective only if said derails assume their closed track position.

8. In a remotely controlled interlocking system, the combination with two railroads crossing each other, of derails on one of said roads for preventing a train on said road crossing the other road, signals for governing the movement of trains over said derails, power operated means for operating said derails, a control relay for controlling said power operated means and controlled from a central office, means for indicating at said office the response of said power operated means to said control relay, other signals on the other of said roads for governing the crossing of trains over said one road, means for preventing operation of said power operated means if one of said other signals indicates proceed, and means for clearing said first mentioned signals effective only if said derails assume their closed track position and there is no train approaching at speed on said one road.

9. In a remotely controlled interlocking system, the combination with two railroads crossing each other, of derails on one of said roads for preventing a train on said road crossing the other road, signals for governing the movement of trains over said derails, power operated means for operating said derails, a control relay for controlling said power operated means and controlled from a central office, means for indicating at said office the response of said power operated means to said control relay, other signals on the other of said roads for governing the crossing of trains over said one road, means for preventing operation of said power operated means if one of said other signals indicates proceed, means for clearing said first mentioned signals effective only if said derails assume their closed track position, and means for indicating at said central office the passage of a train over said derails.

10. In a remotely controlled interlocking system, the combination with two railroads crossing each other, of derails on one of said roads for preventing a train on said road crossing the other road, signals for governing the movement of trains over said derails, power operated means for operating said derails, a control relay for controlling said power operated means and controlled from a central office, means for indicating at said office the response of said power operated means to said control relay, other signals on the other of said roads for governing the crossing of trains over said one road, means for preventing operation of said power operated means if one of said other signals indicates proceed, means for clearing said first mentioned signals effective only if said derails assume their closed track position and there is no train approaching at speed on

said one road and means for indicating at said central office the passage of a train over said derails.

11. In a remotely controlled interlocking system the combination with two railroad systems crossing each other, of wayside signals on one system for blocking the movement of trains over said crossing, derails associated with said signals for enforcing obedience of trains to said signals, a derail relay controlled from a distant tower for controlling said derails, approach locking means for preventing operation of said derails by said derail relay unless there is no train approaching in an approach zone at high speed, a signal control relay controlled from said distant tower for controlling said signals, means for preventing control of said signals by said signal relay unless traffic conditions in advance of such signals are favorable, and means for indicating at said tower the passage of a train over said derails.

In testimony whereof I affix my signature.
